UNITED STATES PATENT OFFICE.

GUSTAV MUELLER, OF CLEVELAND, OHIO.

BOX-LID HOLDER.

No. 822,975.

Specification of Letters Patent.

Patented June 12, 1906.

Application filed September 11, 1905. Serial No. 277,890.

To all whom it may concern:

Be it known that I, GUSTAV MUELLER, a citizen of the United States, residing at Cleveland, in the county of Cuyahoga and State of Ohio, have invented new and useful Improvements in Box-Lid Holders, of which the following is a specification.

This invention is a device for holding a box-lid and also for lifting the box and for disclosing a sign with respect thereto.

It is particularly designed for holding the lids of cigar-boxes and is provided with means whereby it may be adjusted to fit a box-lid of any common size.

15 The device is illustrated in the accompanying drawings, Figure 1 being an edge view thereof when applied to the box. Fig. 2 is a perspective view thereof removed from the box.

20 Referring specifically to the drawings, 6 indicates the box-lid to which the device is applied. The lid is supported thereby in raised or upwardly-inclined position in such manner as to expose the label on the box-cover and also to allow the box to be lifted by means of the attachment, as hereinafter described.

The device consists of two bars 7 and 8, which are slidable lengthwise upon each 30 other, and to hold them together each is provided with tongues 9, which lap over the other bar and form guides in which the bars slide with respect to each other. The upper bar 7 has at the top an enlarged portion 10, 35 on which the sign may be marked, as indicated, for example, in the drawings. This bar also has near the upper end, but below the space for the sign, a tongue 11, which is struck up from the plate and bent down to 40 form a hook of proper size to engage over the upper edge of the box-lid.

The lower bar or member 8 has at its lower end an enlarged part 12, which is curved backwardly or retracted to support the box-lid at the proper angle. This part also has 45 struck up therefrom a tongue 13, which is bent upwardly and arranged to engage under

the lower edge of the box-lid in a manner similar to that of the tongue 11 at the upper edge. At the upper end of the bar 8 it is bent 50 out and down to form a handle 14, properly curved to receive the finger and allow the box to be conveniently lifted.

In the use of the device the bars 7 and 8 are pulled out until the device is long enough 55 to span the box-cover between the tongues 11 and 13. The parts are then pushed together to bring the tongues in engagement with the box-lid. This fastens the device to the box-lid on the rear or outer side thereof, 60 and when the lid is opened the part 12 contacts with the back of the box and holds the lid in position at the desired angle. The part 10 at the top projects above the edge of the lid, and the handle 14 affords convenient 65 means for lifting the box, as in serving customers. After use on one box the device may be readily detached and placed on another, and with the means shown it can be applied to boxes of any ordinary size, since 70 the parts 7 and 8 can be drawn out or pushed in, according to conditions.

What I claim as new, and desire to secure by Letters Patent, is—

A box-lid holder comprising upper and 75 lower members slidably secured together and extensible lengthwise, the upper member having a part extending above the edge of the lid and arranged to receive a sign, and having a downwardly-directed tongue ar- 80 ranged to engage over the upper edge of the lid, and the lower member having a handle at its upper end, an angularly-projecting part at its lower end, and an upwardly-directed tongue arranged to engage the lower edge of 85 the lid.

In testimony whereof I have signed my name to this specification in the presence of two subscribing witnesses.

GUSTAV MUELLER
